ABSTRACT OF THE DISCLOSURE

3-amino-1-aryloxy-2-propanol derivatives in which the aryl nucleus is anthryl, dihydro-anthryl or fluorenyl. These compounds possess β -adrenergic blocking activity and are useful in the treatment of heart diseases.

This invention relates to new homocyclic derivatives which possess β -adrenergic blocking activity and which are therefore useful in the treatment or prophylaxis of heart diseases, for example angina pectoris and cardiac arrhythmias, and in the treatment of hypertension and phaeochromocytoma.

According to the invention we provide homocyclic derivatives of the formula:

wherein R^1 stands for an alkyl, alkenyl or cycloalkyl radical, any of which may optionally be substituted, and R^2 stands for a tricyclic hydrocarbon residue, and the esters thereof, and the salts thereof, and aldehyde condensation products thereof as hereinafter defined.

It is to be understood that the above definition of the homocyclic derivatives of the invention encompasses all possible stereoisomers thereof, and mixtures thereof.

As a suitable value for R^1 when it stands for an alkyl radical there may be mentioned, for example, an alkyl radical of not more than 12 carbon atoms, for example the ethyl, n-propyl, isopropyl, s-butyl, t-butyl or 1-methyl-octyl radical. As a suitable value for R^1 when it stands for a substituted alkyl radical there may be mentioned, for example, an alkyl radical of not more than 12 carbon atoms bearing a hydroxy radical. Thus a specific value for R^1 when it stands for a substituted alkyl radical is the 2-hydroxy-1,1-dimethyl-ethyl radical. As a suitable value for R^1 when it stands for a cycloalkyl radical there may be mentioned, for example, a cycloalkyl radical of not more than 10 carbon atoms, for example the cyclopentyl radical. As a suitable value for R^1 when it stands for an alkenyl radical there may be mentioned, for example, an alkenyl radical of not more than 6 carbon atoms, for example the allyl radical.

As a suitable value for R^2 there may be mentioned, for example, a tricyclic hydrocarbon residue in which two or all three of the rings are unsaturated, for example a tricyclic hydrocarbon residue in which two or all three of the rings are aromatic in nature. The rings in the tricyclic hydrocarbon residue R^2 may, for example, all be 6-membered rings, or one of them may be a 5-membered ring while the remainder are 6-membered. As specific values for R^2 there may be mentioned, for example, an anthryl, dihydro-anthryl or fluorenyl radical.

As suitable esters of the invention there may be mentioned, for example O-esters derived from a saturated or unsaturated aliphatic carboxylic acid, for example a saturated or unsaturated aliphatic carboxylic acid of not more than 20 carbon atoms, for example acetic, palmitic, stearic or oleic acid, or O-esters derived from an aromatic carboxylic acid, for example an aromatic carboxylic acid

2

of not more than 15 carbon atoms, for example benzoic acid.

It is to be understood that in this specification we means by the expression "aldehyde condensation products" oxazolidine derivatives of the formula:

10 wherein R^1 and R^2 have the meanings stated above, and R^3 stands for hydrogen or an alkyl radical, and the salts thereof.

As a suitable value for R^3 when it stands for an alkyl radical, there may be mentioned, for example, an alkyl radical of not more than 6 carbon atoms, for example the isopropyl radical.

Specific homocyclic derivatives of the invention are, for example, 1-(1-anthryloxy)-3-isopropylamino-2-propanol, 1 - (9,10-dihydro-1-anthryloxy)-3-isopropylamino-2-propanol, 1-(4-fluorenyloxy)-3-isopropylamino-2-propanol, 1 - (2-fluorenyloxy)-3-isopropylamino-2-propanol, 1-(1-fluorenyloxy)-3-t-butylamino-2-propanol, 1-(1-fluorenyloxy)-3-isopropylamino-2-propanol and 1-(1-anthryloxy)-3 - (2-hydroxy-1,1-dimethyl-ethylamino)-2-propanol, and the salts thereof.

As suitable salts of the homocyclic derivatives of the invention, including the said oxazolidine derivatives, there may be mentioned acid-addition salts, for example salts derived from inorganic acids, for example hydrochlorides, hydrobromides, phosphates or sulphates, or salts derived from organic acids, for example oxalates, lactates, tartrates, acetates, salicylates, citrates, benzoates, β -naphthoates, adipates or 1,1'-methylene-bis-(2-hydroxy-3-naphthoates), or salts derived from acidic synthetic resins, for example sulphonated polystyrene resins, for example "Zeo-Karb" 225 ("Zeo-Karb" is a Trademark). Relatively insoluble salts, for example the 1,1'-methylene-bis-(2-hydroxy-3-naphthoates), have the advantage that they afford prolonged blood levels of the medicament.

According to a further feature of the invention we provide a process for the manufacture of the homocyclic derivatives of the invention which comprises the interaction of a compound of the formula:

wherein R^2 has the meaning stated above, and A stands for the group

wherein Z stands for a halogen atom, with an amine of the formula R^1NH_2 , wherein R^1 has the meaning stated above.

55 As a suitable value for Z there may be mentioned, for example, a chlorine or bromine atom. The interaction may be accelerated or completed by the application of heat, it may be carried out at atmospheric or at elevated pressure, and it may be carried out in an inert diluent or solvent, for example ethanol.

According to a further feature of the invention I provide a process for the manufacture of the homocyclic derivatives of the invention which comprises the hydrogenolysis of a compound of the formula:

wherein R^1 and R^2 have the meanings stated above, and R^4 stands for a hydrogenolysable radical.

As a suitable value for R^4 there may be mentioned, for example, the benzyl radical. The hydrogenolysis may be effected, for example, by catalytic hydrogenation, for example hydrogenation in the presence of a palladi-

um-on-charcoal catalyst, in an inert diluent or solvent, for example ethanol.

According to a further feature of the invention we provide a process for the manufacture of esters of the invention which comprises the interaction of the appropriate homocyclic derivative, or a salt thereof, with an acylating agent.

As suitable acylating agents there may be mentioned acid halides or anhydrides derived from saturated or unsaturated aliphatic carboxylic acids or from aromatic carboxylic acids, for example acetyl chloride, acetic anhydride or benzoyl chloride. The acylation may be carried out in a diluent or solvent which, in the case where an acid anhydride is used as acylating agent, may conveniently be the acid from which the anhydride is derived.

According to a further feature of the invention we provide a process for the manufacture of the oxazolidine derivatives of the invention which comprises the interaction of the corresponding compound of the formula:

wherein R^1 and R^2 have the meanings stated above, with an aldehyde of the formula $R^3.CHO$, wherein R^3 has the meaning stated above.

The last-named interaction may be carried out in a diluent or solvent, for example ethanol, and it may be accelerated or completed by the application of heat. The water formed during the reaction may be removed by azeotropic distillation using a suitable solvent, for example benzene, toluene or chloroform, as an entraining agent, or it may be removed by means of a dehydrating agent, for example anhydrous potassium carbonate.

As stated above, the homocyclic derivatives of the invention are of value in the treatment or prophylaxis of heart diseases, and in the treatment of hypertension and phaeochromocytoma.

According to a further feature of the invention, therefore, we provide pharmaceutical compositions comprising as active ingredient one or more homocyclic derivatives of the invention, or an ester or esters thereof, or a salt or salts thereof, or one or more aldehyde condensation products as defined hereinbefore, together with a pharmaceutically-acceptable diluent or carrier.

As suitable compositions there may be mentioned for example, tablets, capsules, aqueous or oily solutions, aqueous or oily suspensions, emulsions, injectable aqueous or oily solutions or suspensions, and dispersible powders.

The following is illustrated but not limited by the following examples in which the parts are by weight:

EXAMPLE 1

A mixture of 1 part of 1-(1-anthryloxy)-3-chloro-2-propanol, 10 parts of isopropylamine and 5 parts of ethanol is heated in a sealed vessel at 100° C. for 10 hours. The vessel is cooled and then the excess of isopropylamine and the ethanol are evaporated. The residual gum is shaken together with 50 parts of 2 N-hydrochloric acid and 50 parts of ether. The ethereal layer is separated from the mixture, and the residue is washed 5 times, each time with 50 parts of ether. The said residue is then made alkaline with 10 N-sodium hydroxide solution, and the mixture is extracted 3 times, each time with 50 parts of a mixture of ether and ethyl acetate (1:1 v./v. mixture).

The organic extract is washed with water, dried with anhydrous magnesium sulphate, and then evaporated to dryness. The solid residue is dissolved in 20 parts of ethanol and decolourised with animal charcoal. The mixture is filtered and the filtrate is evaporated to dryness. The solid residue is crystallized from a mixture of petroleum ether (B.P. 100-120° C.) and benzene. There is thus obtained 1-(1-anthryloxy)-3-isopropylamino-2-propanol, M.P. 127-129° C.

The 1-(1-anthryloxy)-3-chloro-2-propanol used as starting material may be obtained as follows:

A mixture of 1 part of 1-hydroxyanthracene, 5 parts of epichlorohydrin and 0.01 part of piperidine is heated at 90-100° C. for 6 hours in an atmosphere of nitrogen. The excess of epichlorohydrin is removed by evaporation under reduced pressure, and the residue thus obtained is dissolved in 50 parts of chloroform. The chloroform solution is washed successively with 50 parts of water, with 10 parts of concentrated hydrochloric acid, and finally with 100 parts of water in two equal portions. The chloroform solution is then dried with anhydrous magnesium sulphate and then evaporated to dryness. There is thus obtained 1-(1-anthryloxy)-3-chloro-2-propanol as an oil.

EXAMPLE 2

A mixture of 1 part of 3-chloro-1-(9,10-dihydro-1-anthryloxy)-2-propanol, 10 parts of isopropylamine and 10 parts of ethanol is heated in a sealed vessel at 100° C. for 10 hours. The vessel is cooled and the excess of isopropylamine and the ethanol are evaporated. The residual gum is shaken together with 50 parts of 2 N-hydrochloric acid and 50 parts of ether. The aqueous acid layer is then separated and washed three times with ether, each time with 50 parts. The aqueous solution is made alkaline with 10 N-sodium hydroxide solution and the mixture is extracted three times, each time with 50 parts of ether. The combined ethereal extracts are washed with 50 parts of water, dried with anhydrous magnesium sulphate, and then evaporated to dryness. The residue is crystallised from a mixture of petroleum ether (B.P. 100-120° C.) and benzene. There is thus obtained 1-(9,10-dihydro-1-anthryloxy)-3-isopropylamino-2-propanol, M.P. 98-99.5° C.

The 3-chloro-1-(9,10-dihydro-1-anthryloxy)-2-propanol used as starting material may be obtained as follows:

A mixture of 1 part of 9,10-dihydro-1-hydroxyanthracene, 5 parts of epichlorohydrin and 0.01 part of piperidine is heated at 90-100° C. for 6 hours in an atmosphere of nitrogen. The excess of epichlorohydrin is removed by evaporation under reduced pressure, and the residue thus obtained is dissolved in 50 parts of chloroform. The chloroform solution is washed successively with 50 parts of water, with 10 parts of concentrated hydrochloric acid, and finally with 100 parts of water in two equal portions. The chloroform solution is then dried with anhydrous magnesium sulphate and then evaporated to dryness. There is thus obtained 3-chloro-1-(9,10-dihydro-1-anthryloxy)-2-propanol as an oil.

EXAMPLE 2

A mixture of 5 parts of 3-chloro-1-(4-fluoroxyloxy)-2-propanol and 40 parts of isopropylamine is heated in a sealed vessel at 100° C. for 10 hours. The vessel is cooled and then the excess of isopropylamine is evaporated. The residual gum is shaken with 200 parts of 2 N-hydrochloric acid. The viscous oil so formed is separated by decantation from the mother liquors and washed 3 times, each time with 50 parts of ether. The mother liquors are washed twice, each time with 50 parts of ether, and then combined with the oil. The mixture is then made alkaline with 10 N-aqueous sodium hydroxide, and extracted 3 times each time with 100 parts of ether. The combined ether extracts are washed with water, dried with anhydrous magnesium sulphate, and then evaporated to dryness. The solid residue is crystallised from petroleum ether (B.P. 80-100° C.) and then from a mixture of petroleum ether (B.P. 40-60° C.) and benzene. There is thus obtained 1-(4-fluoroxyloxy)-3-isopropylamino-2-propanol, M.P. 118-119.5° C.

The 3-chloro-1-(4-fluoroxyloxy)-2-propanol used as starting material may be obtained as follows:

A mixture of 5 parts of 4-hydroxyfluorene, 25 parts of epichlorohydrin and 0.05 part of piperidine is heated at 90-100° C. for 6 hours. The excess of epichlorohydrin is

removed by evaporation under reduced pressure, and the residue thus obtained is dissolved in 100 parts of chloroform. The chloroform solution is washed successively with 100 parts of water, with 20 parts of concentrated hydrochloric acid, and finally with 100 parts of water in two equal portions. The chloroform solution is dried with anhydrous magnesium sulphate and then evaporated to dryness. There is thus obtained 3-chloro-1-(4-fluorenyloxy)-2-propanol as an oil.

EXAMPLE 4

The process described in Example 3 is repeated except that the 5 parts of 3-chloro-1-(4-fluorenyloxy)-2-propanol are replaced by 5 parts of 3-chloro-1-(1-fluorenyloxy)-2-propanol. There is thus obtained 1-(1-fluorenyloxy)-2-isopropylamino-2-propanol, M.P. 96.5-97.5° C. (crystallised from petroleum ether, B.P. 80-100° C.).

The 3-chloro-1-(1-fluorenyloxy)-2-propanol used as starting material is obtained by repeating the process described in Example 3 for the preparation of 3-chloro-1-(4-fluorenyloxy)-2-propanol except that the 5 parts of 4-hydroxyfluorene are replaced by 5 parts of 1-hydroxyfluorene. There is thus obtained 3-chloro-1-(1-fluorenyloxy)-2-propanol as an oil.

EXAMPLE 5

The process described in Example 3 is repeated except that the 5 parts of 3-chloro-1-(4-fluorenyloxy)-2-propanol are replaced by 5 parts of 3-chloro-1-(2-fluorenyloxy)-2-propanol. There is thus obtained 1-(2-fluorenyloxy)-3-isopropylamino-2-propanol, M.P. 127-129° C. (crystallised from petroleum ether, B.P. 100-120° C. and then from a mixture of petroleum ether, B.P. 100-120° C. and benzene).

The 3-chloro-1-(2-fluorenyloxy)-2-propanol used as starting material is obtained by repeating the process described in Example 3 for the preparation of 3-chloro-1-(4-fluorenyloxy)-2-propanol except that the 5 parts of 4-hydroxyfluorene are replaced by 5 parts of 2-hydroxyfluorene. There is thus obtained 3-chloro-1-(2-fluorenyloxy)-2-propanol as an oil.

EXAMPLE 6

The process described in Example 3 is repeated except that the 5 parts of 3-chloro-1-(4-fluorenyloxy)-2-propanol are replaced by 5 parts of 3-chloro-1-(3-fluorenyloxy)-2-propanol. There is thus obtained 1-(3-fluorenyloxy)-3-isopropylamino-2-propanol, M.P. 117-121° C. (Crystallised from petroleum ether, B.P. 80-100° C.).

The 3-chloro-1-(3-fluorenyloxy)-2-propanol used as starting material is obtained by repeating the process described in Example 3 for the preparation of 3-chloro-1-(4-fluorenyloxy)-2-propanol except that the 5 parts of 4-hydroxyfluorene are replaced by 5 parts of 3-hydroxyfluorene. There is thus obtained 3-chloro-1-(3-fluorenyloxy)-2-propanol as an oil.

EXAMPLE 7

A mixture of 0.5 part of 3-chloro-1-(1-fluorenyloxy)-2-propanol and 5 parts of t-butylamine is heated in a sealed vessel at 100° C. for 10 hours. The vessel is cooled and the excess of isopropylamine is evaporated. The residual gum is shaken with 50 parts of 2 N-hydrochloric acid. The viscous oil so formed is separated from the mother liquors by decantation and washed 3 times, each time with 20 parts of ether. The mother liquors are washed twice, each time with 20 parts of ether and then combined with the oil. The mixture is then made alkaline with 10 N-aqueous sodium hydroxide, and extracted 3 times, each time with 50 parts of ether. The combined ether extracts are washed with water, dried with anhydrous magnesium sulphate and filtered. To the filtrate is added an ethereal solution of oxalic acid. The mixture is filtered and the solid residue is washed with ether and then crystallised from ethanol. It is then added to 30 parts of 2 N-aqueous potassium hy-

dioxide and the mixture is extracted 3 times each time with 30 parts of ether. The ethereal extracts are washed with water, dried with anhydrous magnesium sulphate and evaporated to dryness. The residual gum is triturated with petroleum ether, B.P. 40-60° C. and the solid obtained is crystallised from petroleum ether, B.P. 60-80° C. There is thus obtained 1-(1-fluorenyloxy)-3-t-butylamino-2-propanol, M.P. 94-95.5° C.

EXAMPLE 8

10 The process described in Example 1 is repeated except that the 10 parts of isopropylamine are replaced by 10 parts of allylamine.

15 The extraction of the product from alkaline solution is carried out using ether instead of a mixture of ether and ethyl acetate. There is thus obtained 3-allylamino-1-(1-anthryloxy)-2-propanol, M.P. 110.5-113° C. (Crystallised from petroleum ether, B.P. 80-100° C., and then from a mixing of petroleum ether, B.P. 60-80° C. and benzene.)

EXAMPLE 9

20 The process described in Example 1 is repeated except that the 10 parts of isopropylamine are replaced by 10 parts of cyclopentylamine. The extraction procedure is modified as described in Example 8. There is thus obtained 1-(1-anthryloxy)-3-cyclopentylamino-2-propanol, M.P. 109.5-111° C. (Crystallised first from petroleum ether, 100-120° C., and then from a mixture of petroleum ether, B.P. 40-60° C. and benzene.)

EXAMPLE 10

25 The process described in Example 1 is repeated except that the 10 parts of isopropylamine are replaced by 10 parts of 2-amino-2-methylpropanol. The extraction procedure is modified as described in Example 8. There is thus obtained 1-(1-anthryloxy)-3-(2-hydroxy-1,1-dimethylaminol)-2-propanol, M.P. 138.5-141° C. (Crystallised from a mixture of petroleum ether, B.P. 80-100° C. and benzene.)

EXAMPLE 11

30 1 part of 1-hydroxyfluorene is dissolved in a solution of 0.26 part of sodium hydroxide in 5 parts of water. The solution is stirred and kept at a temperature of 10-20° C. while 0.64 part of epichlorohydrin is added. The mixture is stirred at ambient temperature during 18 hours, and is then extracted with 40 parts of chloroform. The chloroform extracts are washed with water, dried over anhydrous magnesium sulphate, and the chloroform is removed by distillation under reduced pressure. There is thus obtained 1-(1-fluorenyloxy)-2,3-epoxypropanol as an oil, which is dissolved in 10 parts of isopropylamine and the mixture is heated at 90-100° C. during 2 hours. The excess of isopropylamine is then removed by distillation under reduced pressure and the residual gum is shaken with 50 parts of 2 N-hydrochloric acid. The viscous oil so formed is separated from the mother liquors by decantation and washed 3 times, each time with 10 parts of ether. The mother liquors are washed twice, each time with 20 parts of ether, and then combined with the oil. The mixture is then made alkaline with 10 N-aqueous hydroxide, and extracted 3 times, each time with 50 parts of ether. The combined ether extracts are washed with water, dried with anhydrous magnesium sulphate and then evaporated to dryness. The solid residue is crystallised from petroleum ether, B.P. 80-100° C. and then from a mixture of petroleum ether, B.P. 60-80° C. and benzene. There is thus obtained 1-(1-fluorenyloxy)-3-isopropylamino-2-propanol, M.P. 95-97° C.

EXAMPLE 12

70 A mixture of 3 parts of 3-(N-benzyl-N-isopropylamino)-1-(4-fluorenyloxy)-2-propanol, 20 parts of ethanol, 1 part of a saturated solution of hydrogen chloride in ether and 0.2 part of a 10% palladium-on-charcoal catalyst is shaken in an atmosphere of hydrogen at ambient

temperature and atmospheric pressure until no further uptake of hydrogen is observed. The mixture is filtered and the ethanol is removed from the filtrate by distillation under reduced pressure. The residue is triturated with 5 parts of a saturated solution of hydrogen chloride in ether, and then with 20 parts of ethyl acetate. The solid obtained is crystallised from a mixture of ethanol and ether. There is thus obtained 1-(4-fluorenyloxy)-3-isopropylamino-2-propanol hydrochloride, M.P. 183-185° C.

The 3-(N-benzyl-N-isopropylamino)-1-(4-fluorenyloxy)-2-propanol used as starting material is obtained as follows:

1.84 parts of 4-hydroxyfluorene are dissolved in a solution of sodium ethoxide prepared from 0.23 part of sodium and 10 parts of ethanol. 2.05 parts of 3-(N-benzyl-N-isopropylamino)-1,2-epoxypropane are added, and the mixture is heated in a sealed vessel at 100° C. during 10 hours. The vessel is cooled, the contents are washed out with 20 parts of ethanol, and the ethanol is removed by distillation under reduced pressure. The residual gum is shaken with 50 parts of 2 N-hydrochloric acid. The viscous oil so formed is separated from the mother liquors by decantation and washed 3 times, each time with 50 parts of ether. The mother liquors are washed twice each time with 50 parts of ether, and then combined with the oil. The mixture is then made alkaline with 10 N-aqueous sodium hydroxide and extracted 3 times, each time with 50 parts of ether. The combined ether extracts are washed with water, dried over anhydrous magnesium sulphate and evaporated to dryness. There is thus obtained 3-(N-benzyl-N-isopropylamino)-1-(4-fluorenyloxy)-2-propanol as an oil. A small aliquot of this oil is converted to the picrate by treatment with picric acid in ethanol. The picrate is crystallised from aqueous ethanol and then from ethanol. There is thus obtained 3-(N-benzyl-N-isopropylamino)-1-(4-fluorenyloxy)-2-propanol picrate M.P. 175-180° C.

EXAMPLE 13

0.2 part of 1-(4-fluorenyloxy)-3-isopropylamino-2-propanol hydrochloride is heated with 6 parts of acetyl chloride at 90-100° C. for 1 hour. The solution thus obtained is then evaporated to dryness under reduced pressure and the residual oil is triturated with 30 parts of ether. The solid so formed is crystallised from a mixture of ethanol and ether. There is thus obtained 1-(4-fluorenyloxymethyl)-2-isopropylaminoethyl acetate, M.P. 169-172° C.

The 1-(4-fluorenyloxy)-3-isopropylamino-2-propanol hydrochloride used as starting material is obtained from the base described in Example 3. The free base is dissolved in ether and treated with a saturated ethereal solution of hydrogen chloride. The solid so formed is crystallised from a mixture of ethanol and ether. There is thus obtained 1-(4-fluorenyloxy)-3-isopropylamino-2-propanol hydrochloride, M.P. 183-185° C.

EXAMPLE 14

A solution of 0.5 part of 1-(4-fluorenyloxy)-3-isopropylamino-2-propanol and 3 parts of 40% formalin in 20 parts of ethanol is heated under reflux during 18 hours, and then the solvent is removed by evaporation under reduced pressure. The residual oil is triturated with a small volume of petroleum ether, B.P. 40-60° C., and the resulting solid is crystallised from petroleum ether, B.P. 40-60° C., after removal by filtration of a small amount of insoluble material. There is thus obtained 5-(4-fluorenyloxymethyl)-3-isopropylazolidine, M.P. 79-83° C.

EXAMPLE 15

A mixture of 50 parts of 1-(4-fluorenyloxy)-3-isopropylamino-2-propanol, 125 parts of maize starch, 270 parts of calcium phosphate and 1 part of magnesium stearate is compressed, and the compressed material is

then broken down into granules by passage through a 16-mesh screen. The resultant granules are compressed into tablets according to the known art. There are thus obtained tablets which are suitable for oral use for therapeutic purposes.

The 50 parts of 1-(4-fluorenyloxy)-3-isopropylamino-2-propanol are replaced by 50 parts of 1-(1-anthryloxy)-3-isopropylamino-2-propanol, 1-(1-fluorenyloxy)-3-isopropylamino-2-propanol, 1-(1-fluorenyloxy)-3-t-butylamino-2-propanol or 1-(2-fluorenyloxy)-3-isopropylamino-2-propanol, and there are thus obtained in a similar manner, tablets suitable for therapeutic use.

What I claim is:

1. A homocyclic compound selected from the group consisting of compounds of the formula:

wherein R' is selected from the group consisting of alkyl of 1-9 carbon atoms, 2-hydroxy-1,1-dimethylethyl, cyclopentyl and allyl, and R² is selected from the group consisting of anthryl, dihydroanthryl and fluorenyl, and the pharmaceutically-acceptable acid addition salts thereof.

2. A compound selected from the group consisting of 1-(1-anthryloxy)-3-isopropylamino-2-propanol and the pharmaceutically-acceptable acid addition salts thereof.

3. A compound selected from the group consisting of 1-(9,10-dihydro-1-anthryloxy)-3-isopropylamino-2-propanol and the pharmaceutically-acceptable acid addition salts thereof.

4. A compound selected from the group consisting of 1-(4-fluorenyloxy)-3-isopropylamino-2-propanol and the pharmaceutically-acceptable acid addition salts thereof.

5. A compound selected from the group consisting of 1-(2-fluorenyloxy)-3-isopropylamino-2-propanol and the pharmaceutically-acceptable acid addition salts thereof.

6. A compound selected from the group consisting of 1-(1-fluorenyloxy)-3-t-butylamino-2-propanol and the pharmaceutically-acceptable acid addition salts thereof.

7. A compound selected from the group consisting of 1-(1-fluorenyloxy)-3-isopropylamino-2-propanol and the pharmaceutically-acceptable acid addition salts thereof.

8. A compound selected from the group consisting of 1-(1-anthryloxy)-3-(2-hydroxy-1,1-dimethylethylamino)-2-propanol and the pharmaceutically-acceptable acid addition salts thereof.

9. A salt as claimed in claim 1 which is selected from the group consisting of the hydrochlorides, hydrobromides, phosphates or sulphates, oxalates, lactates, tartrates, acetates, salicylates, citrates, benzoates, β -naphthoates, adipates and 1,1'-methylene-bis-(2-hydroxy-3-naphthoates), and salts derived from acidic synthetic resins.
